US00D611662S

(12) **United States Design Patent**
Vosbikian

(10) **Patent No.:** **US D611,662 S**
(45) **Date of Patent:** **** Mar. 9, 2010**

(54) **BIRD FEED TRAY**

(75) Inventor: **Peter S. Vosbikian**, Moorestown, NJ
(US)

(73) Assignee: **Zenith Innovation, LLC**, Delran, NJ
(US)

(**) Term: **14 Years**

(21) Appl. No.: **29/314,627**

(22) Filed: **Apr. 15, 2009**

(51) LOC (9) Cl. **30-03**

(52) U.S. Cl. **D30/128**

(58) Field of Classification Search **D30/121, D30/124, 126-129, 133, 199; 119/52.2, 119/51.5, 61.5, 57.8, 57.9, 52.3, 61.1, 531, 119/63; 47/67, 83; 248/318; D11/164, 152**

Primary Examiner—Susan Moon Lee

(74) Attorney, Agent, or Firm—Stuart M. Goldstein

(57) **CLAIM**

The ornamental design for a bird feed tray, as shown and described.

DESCRIPTION

FIG. 1 is an isometric view of a bird feed tray of the present invention as it would be installed beneath a pole mounted bird feeder.

FIG. 2 is a top isometric view of the bird feed tray of the present invention.

FIG. 3 is a top view of the bird feed tray of the present invention.

FIG. 4 is a bottom view of the bird feed tray of the present invention.

FIG. 5 is a front view of the bird feed tray of the present invention.

FIG. 6 is a rear view of the bird feed tray of the present invention.

FIG. 7 is a right side view of the bird feed tray of the present invention; and,

FIG. 8 is a left side view of the bird feed tray of the present invention.

The elements in broken line are environmentally illustrative and are not claimed.

1 Claim, 5 Drawing Sheets
